(57) **CLAIM**

The ornamental design for a trigger pump dispenser shroud, as shown and described.

DESCRIPTION

FIG. 1 is a perspective view of a trigger pump dispenser shroud showing our new design;

FIG. 2 is a left side elevational view;

FIG. 3 is a top plan view;

FIG. 4 is a rear elevational view;

FIG. 5 is a front elevational view;

FIG. 6 is a bottom plan view;

FIG. 7 is a perspective view of a modified form of the trigger pump dispenser shroud;

FIG. 8 is a left side elevational view;

FIG. 9 is a top plan view;

FIG. 10 is a rear elevational view;

FIG. 11 is a front elevational view; and,

FIG. 12 is a bottom plan view.

The left side elevations are mirror images of the right side elevations.
